SOLAR HEATER

John David McCain, Phoenix, Ariz.

Application October 17, 1938, Serial No. 235,471

2 Claims. (CL 126—271)

My invention relates to solar heaters of the type adapted to collect the rays of the sun and direct the concentrated rays to a focal point on an object to be heated.

One of the objects of my invention is to provide such a device of simple, rugged construction which may be easily and cheaply manufactured and easily operated;

Further, to provide such a device wherein no moving parts are necessary to enable the sun's rays to be focused upon the desired object throughout approximately the entire day.

A further object is to provide a device of this character in which adjustment of the focal point is not critical and in which adjustment may be made to allow for the seasonal change in the apparent path of the sun easily and quickly.

A further object is to provide a device of this kind in which the concentrating lens may be easily replaceable in case it becomes damaged in use; and

A further object is to provide a device of the character mentioned in which a lens of novel type is combined with apparatus for receiving the heat concentrated and converting same into a form of energy which may be easily applied to useful work.

Other objects will appear hereinafter.

I attain the foregoing objects by means of the apparatus, device and mechanical constructions illustrated in the accompanying drawing in which

Figure 1 is a side elevational view of my type of lens;

Figure 2, an end or edgewise view thereof;

Figure 3, a side elevation of the device adapted to utilize said lens for the production of vapor from fluids, or the like, with certain portions thereof shown in section to better illustrate their construction.

Similar numerals refer to similar parts in all views.

Considering first, the lens, attention is directed to Figures 1 and 2. The lens, or refractor, is made of cast and polished glass in the general shape of a ring, a section of which is uniformly convex. Thus formed, I have provided a continuously annular convex lens adapted to concentrate the sun's rays striking its outer periphery within a semi-cylindrical focal area having an axis coinciding with that of the ring.

In use, this lens is positioned with its axis at right angles to the plane of the ecliptic; that is, so that its central diametric plane coincides with the ecliptic and the apparent path of the sun from horizon to horizon. When thus posi-

tioned, only the upper portion of the lens is used at any one time. It might be presumed that it would be easier to construct an arcuate semi-circular lens of this nature. However, I have found that it is more efficient to construct a lens in circular form, as here illustrated. In this form it may be easier cast and ground that would be the case with semi-circular arcuate segments. The diameter of the lens ring is such that, with a given sectional convexity of the annular body of the lens, light will be focused within an area around the periphery of cylinder 8. As the sun moves from horizon to horizon, the focused rays move in an annular path, as indicated by numeral 5, around the central portion of this cylinder. Concentration of light rays 3 is effected principally by the convexity of the section 7 of the ring but secondarily by the annular convex shape of the ring body. Therefore, it may be said that the focal area of the lens body lies within an annular space surrounding the axis of the ring 2. At any one time the point or area of concentrated light and heat is directed on one spot or portion of the surface of the generator cylinder. As the sun moves, this place of concentration moves accordingly around a selected portion of the cylinder. In order to maintain an even focus, the axis of the cylinder, therefore, must coincide with the axis of the ring. Further, the radius of the ring must be proportioned so that, with a given (or predetermined) convexity of the ring section 7, the focal area will lie approximately upon the surface of the generator cylinder. The generator, of course, may have a spherical shape or a semi-cylindrical shape rather than that shown. In all cases, however, it should have an annular surface, the axis of which coincides with the axis of the ring body. The position of this focal area, as generated for the entire ring, is indicated by numeral 4.

It is to be understood that the sun's rays are not concentrated to a fine point upon the surface of the generator within the focal area but only sufficiently to obtain the degree of heat required. In some instances, therefore, with a lens of the same proportions, a generator having a larger, or another having a similar cylinder may be used. The focal area in such cases, would have a greater or less diameter depending upon the size of the generator cylinder, and broadly might be better termed as a focal space surrounding the axis of the ring. The outer periphery of the ring is indicated by numeral 5, the inner periphery by numeral 6 and the relative convex-

ity of these surfaces shown in section at 7 in Figure 3.

An adaption of this type of lens to one form of device is illustrated in Figure 3. Here numeral 8 indicates a closed metallic cylinder which may be termed a generator or boiler, having an outlet tube 9 at its upper and right hand and an inlet 10 axially positioned and extending from the right hand end into the body of the cylinder as indicated by dotted lines 11, to a position near the left hand end of the cylinder. This inlet or return pipe is provided with a check valve 12.

This cylinder is mounted on trunnions 14, supported in a yoke 15 near its right hand end and on an axially extending rod 16 at its left hand end. This rod is held by thumb adjusting nut and bolt 17 in an arcuate slot 18 in the arc shaped supporting bar 19. The lens 2 is positioned with its axis coinciding with that of generator cylinder 8 and supported on a frame 20 which, in turn, is supported on a sleeve 21 fitted around cylinder 8. This sleeve may have a comparatively loose fit around the cylinder and thus permit both longitudinal axial adjustment of the lens along the body of cylinder 8 as well as circumferential rotary movement of the lens when desired.

In order to control the amount of heat applied to cylinder 8 at the area of concentration 4, I have provided a cylindrical mask 22 of metal, or other suitable material, mounted on spokes 23 attached to a hub 24, and this, in turn, mounted on cylinder 8 to provide a sliding fit so that the entire mask assembly may be easily moved longitudinally on the cylinder by control rod 25, which may be connected by levers and rods or cables to any position desired for remote control.

When thus set up, the device may be positioned so that the axis of the ring is at right angles to the plane of the ecliptic. The axis of the ring is perpendicular to the dotted line E—E, which represents a plane bisecting the annular body of the ring. When the axis of the cylinder and ring is placed in a north and south position the plane E—E may be made to coincide with the ecliptic by varying the position of rod 6 in support 19. Thus the position of the lens may be adjusted to have the correct angular position necessary to maintain the proper focus according to the season. Liquid to be vaporized is then introduced into cylinder 8 through pipe 10. This may be water which is desired to be converted into steam for the purpose of operating a machine or it may be liquid containing gas such as Freon to be driven off under pressure and used for obtaining refrigeration. In either case, after boiling or vaporization, due to the heat applied to cylinder 8, at the focal point, vapor escapes through the outlet pipe 9 and condensed liquid is returned from a closed circuit through check valve 12 and inlet 10, to the lower or left hand portion of cylinder 8.

When it is desired to reduce the action of the device while the sun is shining, a portion of the rays to be concentrated is cut off by moving the mask 22 in the direction indicated by the arrow 26. Thus regulation may be effected.

Aside from the use above illustrated and described, the device may be used to heat a semi-horizontal portion of vent pipe leading from a room to be ventilated to the atmosphere. By heating a portion of this vent pipe with a lens of this type, a hot spot is created on the pipe, air therewithin expanded, and a draft created; all without the necessity of any moving parts whatever.

15 Other uses are readily apparent.

Having now described my invention and explained its uses, it will be apparent to those familiar with the art that the device is subject to numerous changes and modifications, all of 20 which, however, will remain within the spirit of the invention. Therefore, I wish to be bound only by the following claims:

I claim:

1. A solar heater comprising, in combination, 25 an annular glass refractor lens having a convex section adapted to focus the sun's rays on a focal area within an annular space surrounding its axis of curvature and between said axis and the body of the lens, a generator adapted to contain liquids to be vaporized comprising a closed vessel provided with outlet and inlet connections positioned with a portion thereof within the focal area of said refractor lens, and means of support for said refractor lens and said generator, whereby they may be adjusted to maintain the axis of said lens substantially perpendicular to the plane of the ecliptic.

2. A solar heater comprising, in combination, 30 a glass refractor lens having a ring-shaped annular body with a convex section adapted to focus the sun's rays on a focal area within an annular space surrounding its axis between said axis and the body of the lens, a generator adapted to evaporate liquids including a tubular container having an outlet pipe at its upper end, and an inlet pipe communicating with its lower end, adjustable means for supporting said refractor on said generator so that a predetermined portion of said generator lies within the focal area of said refractor, means for adjustably supporting said refractor and generator to permit the central diametrical plane of said refractor to be positioned to coincide with the plane of the ecliptic throughout seasonal variation and maintain the focal relation of said refractor and generator, and means for controlling the amount of heat at said focal area, including adjustable masking means movable to a position between said refractor and said focal area.

JOHN DAVID McCAIN.
